J. STÄUBLI

REFUSE RECEPTACLE

Filed Sept. 19, 1922

J. Stäubli
INVENTOR
BY
F. Scherzer
ATTORNEY

UNITED STATES PATENT OFFICE.

JOHN STÄUBLI, OF SYRACUSE, NEW YORK.

REFUSE RECEPTACLE.

Application filed September 19, 1922. Serial No. 589,072.

To all whom it may concern:

Be it known that I, JOHN STÄUBLI, a citizen of Switzerland, residing at Syracuse, in the county of Onondaga and State of New York, have invented certain new and useful Improvements in Refuse Receptacles, of which the following is a specification.

This invention relates to sanitary refuse receptacles, and has for one of its main objects the provision of a relatively large receptacle which can be conveniently sunken or embedded on a farm, preferably near the cattle pens, for receiving the various animal offal and storing the same in a sanitary manner until disposal thereof is made.

Another object is to provide a tank which is completely sealed when not in use thereby keeping the atmosphere clear and also preventing obnoxious odors so prevalent with the means in present day use.

Still another object is to provide a small door at the side of the receptacle which can be readily opened by the pressure of the foot, this being an important feature as the hands of the farmer are generally occupied while disposing said offal.

These and other objects will become apparent in the description below in which characters of reference refer to the like-named parts in the drawing.

Referring briefly to the drawing, Figure 1 represents a top plan view of the sanitary refuse tank.

Figure 2 is a sectional elevational view of the same, taken on the line 2—2 of Figure 1.

Figure 3 is a side elevational view of the receiving chute, showing the door in closed position.

Figure 4 is a side elevation of the same but showing the door in open position.

Referring more in detail to the drawing, the numeral 10 represents the side wall of a comparatively large refuse tank, and has a cover 11 and a conical shaped bottom securely riveted thereto.

A door 13 is adapted to slide in the recesses formed between the cover 11 and angle irons 14, the latter being riveted to the said cover. When it is desired to dispose of the refuse and offal in the tank, the door handle 15 is given an arcuate swing thereby exposing an opening 16 thru which working access is gained.

It is to be understood that the refuse tank is buried in the soil and exposes the cover

member 11 and the upper end of a chute 17 only. The chute 17 has an angular bottom surface 17' and is open throughout its length on the side of the tank so that refuse will readily find its way into the tank chamber after being thrown down the chute.

Bearing brackets 18 secured to the opposing upper corners of the chute are adapted to pivotally engage pivot studs 20 of the trap 19. To facilitate the opening of trap 19 by the foot, a foot lever 21 is pivoted on pin 22 and has an open slot 23 at the opposite end. Depressing foot lever 21 will cause the bell crank 25 to be rotated about the pin 28 by pin 24 at the short end of the bell crank engaged in slot 23 of the foot lever.

As bell crank 25 moves upwardly, trap 19 having the pin 26 engaged in lever slot 27 will also be rotated and the chute will thus be opened. As pressure on the foot lever is released trap 19 will immediately close to position shown in Figure 3. It is obvious that the refuse tank can always be kept in a sanitary condition as the trap thereon will always fall into the closed position.

I claim:

1. A refuse tank having cover and bottom members, and adapted to be buried in the soil, a door slidably mounted under the cover and adapted to close an opening in the same, a chute mounted adjacent the tank wall, a trap pivotally secured to the upper end of the chute, the chute having inclined side edges, and means for opening said trap, by a downward movement of the foot.

2. A refuse tank comprising a cover and bottom members, a door slidably mounted under the cover member, a chute communicating with the tank and having a trap pivotally secured to its upper end, a foot lever pivotally secured to one side of the chute, a slotted bell crank having a short arm mounted on the chute and having the trap door engaged in the slot of bell crank, the latter being adapted to open the trap when the foot lever is depressed, and means for automatically closing the trap when pressure on the foot lever is released.

3. A refuse tank comprising side walls having a cover and a conical bottom, a chute mounted adjacent the side wall, an opening formed in the wall of the tank communicating directly with the chute, the upper edges of the chute being inclined outwardly, brackets mounted on the lower portion of

the edges, a trap pivotally supported by said brackets and adapted to normally cover the open end of the chute, a pin projecting from one side of the trap, a bell crank pivoted on the chute and having a slotted arm, said slotted arm engaging the pin on the trap, the opposite arm of the bell crank having a pin thereon, a foot lever pivoted intermediate its length and being slotted at one

end, the slotted end of said foot lever engaging the pin on the bell crank, a high end of said foot lever when depressed being adapted to rotate the bell crank and open the trap to an inclined position, said trap being adapted to normally fall into closed position 15 of its own accord.

In witness whereof I affix my signature.
JOHN STÄUBLI.
